HEATING OF FLUIDS

Marion W. Barnes, Chicago, Ill., assignor to Universal Oil Products Company, Chicago, Ill., a corporation of Delaware

Application May 4, 1933, Serial No. 669,325

11 Claims. (Cl. 196—51)

This invention particularly refers to an improved method and means of heating fluids such as hydrocarbon oils to the high temperatures required for their conversion and more particularly refers to improvements in the type of furnace wherein separate combustion zones are employed, heat derived from one zone, primarily by radiation, being utilized to quickly heat the oil to the desired conversion temperature while heat derived from the other combustion zone, also primarily by radiation, is utilized to maintain the oil at a fairly constant conversion temperature for a predetermined time and combustion gases from both combustion zones being utilized to heat the incoming oil to a temperature below the desired conversion temperature attained by the oil in the first mentioned combustion zone.

One of the principal problems in the design of furnaces of the character above described, wherein the oil is first heated to the desired conversion temperature and then maintained at or near the attained temperature for a predetermined time, has been the large drop in pressure due to friction through the fluid conduit, which is necessarily of unusual length due to the time element required in the soaking section, i. e. that section wherein the oil is maintained at a fairly constant temperature for a predetermined time. This necessitates exceptionally high pressures in the first heating stages in order to maintain the desired conversion pressure in the soaking section and obviously greatly increases pumping costs as well as necessitating the use of thicker wall tubes and fittings to maintain the proper safety factor and obviate unusual fire and explosion hazard. An increase in the diameter of the fluid conduit for the purpose of reducing the pressure drop for a given volume of oil flowing therethrough, due to friction, greatly reduces the effectiveness of the heating surface measured over a given tube area, since the cross-sectional area, which determines the volume of the tube, increases out of proportion to the increased circumference, which determines the heating surface. Therefore, the heating surface per unit volume of oil undergoing treatment is decreased by increasing the tube diameter.

In the present invention in order to maintain the desired ratio of heating surface to tube volume and still minimize the pressure drop, due to friction through the fluid conduit, the stream of oil during its passage through a portion of the fluid conduit is divided into two substantially

equal streams, parallel rows of tubes of the usual size being employed for the two streams. This necessitates the use of both exposed and shielded tubes in that portion of the fluid conduit where heat is absorbed principally by radiation.

Obviously, if one stream of hydrocarbon oil is passed through the shielded row of tubes and the other stream through the exposed row of tubes, both streams will not be subjected to the same heating conditions, the stream in the exposed row being subjected to a higher rate of heating and consequently heated to a higher temperature than the stream in the shielded row. Under these conditions a portion (one stream) of the oil would be subjected to a much more severe cracking condition than another portion (the other stream) of the same oil and the effects of such unequal heating are accumulative. The increased vaporization of the more highly heated stream increases the velocity and friction through that portion of the fluid conduit through which it passes thereby causing a larger proportion of the oil to pass through that portion of the fluid conduit which is subjected to less severe heating conditions and further decreasing the rate of heating and the temperature to which the oil is heated in this portion of the fluid conduit. This tends to bring about a condition wherein a predominant quantity of the total oil passes through the shielded row of tubes and is heated therein to a temperature substantially below that desired, while only a small quantity of the total oil passes through the exposed row of tubes in a highly vaporous condition and is heated to a temperature greatly in excess of that desired.

In the present invention in order to effect substantially equal heating in the two streams and to maintain the quantities of oil in each stream substantially equal, a criss-cross flow is employed through the shielded and exposed rows of tubes, each of the two streams passing first through a tube in the exposed row and then through a tube in the shielded row, then through another tube in the exposed row and so on throughout the length of the two rows of tubes, different streams of oil flowing through adjacent tubes in each row, the number of shielded tubes and the number of exposed tubes in each stream being equal. In this manner regardless of different heating conditions in the exposed and shielded rows and even though heating conditions may vary in different portions of the same row, substantially equal heating is obtained in both streams and, due to equal heating and

equal friction in the two streams, a substantially equal quantity of oil may be maintained in both streams.

In the preferred embodiment of the invention the oil to be subjected to conversion is divided into two substantially equal streams which pass simultaneously and in series through an equal number of tubes, comprising similar portions of the fluid conduit located in the convection section of the furnace, wherein the two streams are subjected to equal heating by fluid heat derived from the combustion gases from both combustion zones of the furnace. The two streams of oil then join and the commingled stream passes in series through adjacent tubes comprising single rows of tubes adjacent the floor and adjacent the roof of one combustion zone, whereby the oil is quickly brought to the desired conversion temperature primarily by radiant heat derived from the hot combustion gases and the refractory walls of the furnace. The oil is then again divided into two substantially equal streams, the flow of which forms a criss-cross path, as previously described, through adjacent tubes comprising an exposed and a shielded row of tubes adjacent the roof and adjacent the floor of the other combustion zone of the furnace, whereby the two streams are subjected to substantially equal heating by means of primarily radiant heat derived from the combustion gases and refractory furnace walls of this portion of the furnace, the heating in this latter stage being of sufficient intensity to maintain the oil at a substantially uniform conversion temperature during its passage therethrough, said uniform conversion temperature being not appreciably (say 50° F.) above or below the maximum temperature attained in the preceding portion of the fluid conduit.

Series flow through tubes arranged in single exposed rows in that portion of the fluid conduit wherein the oil is brought to the desired conversion temperature is preferred in order to maintain a high velocity and a high rate of heating in this portion of the heating stage of the process while split flow, such as described, is preferred in the soaking section of the fluid conduit where such a high rate of heating is not required, due to the fact that the oil is simply maintained at a substantially constant temperature in this portion of the heating stage, and split flow may also be employed in the so-called convection heating zone of the furnace wherein fluid heat from the combustion gases is imparted to the oil, due to the fact that most of the latent heat of vaporization and of cracking is added in subsequent portions of the heating coil, obviating the necessity of high rates of heating in the convection section.

One feature of the invention embodies, in conjunction with a fluid conduit comprising shielded and exposed rows of tubes subjected to heating primarily by radiation, the improved flow therethrough obtained by connecting diagonally adjacent tubes in the different rows and alternate tubes in the same row in series and passing therethrough substantially equal quantities of oil in separate streams in such a manner that the number of shielded tubes in each stream is equal to the number of shielded tubes in the other stream and the number of exposed tubes in each stream is equal to the number of exposed tubes in the other stream so that each of the streams of substantially equal quantities

of oil are subjected to substantially equal heating.

The accompanying diagrammatic drawing is a sectional elevation in cross-section of one specific form of furnace embodying the various features of the present invention and in which the process of the invention and the desired results may be accomplished.

Referring to the drawing, the outer walls of the furnace are indicated at 1 and comprise the usual side walls, end walls, roof and floor of any desired standard construction. The interior of the furnace comprises two combustion zones designated, respectively, as 2 and 3 and a fluid heating or convection zone 4, which latter is separated from the combustion zones 2 and 3 by the respective bridge walls 5 and 6.

Fuel is supplied by means of any suitable form of burners, (not shown) through one or a plurality of firing tunnels 7 to each of the combustion zones 2 and 3. Any suitable fuel such as oil, gas or pulverized solid fuel being supplied, together with a portion of the air required for combustion, through the central portions 8 of the tunnels while the desired auxiliary air or steam or both is supplied to the combustion zone through tunnels 9 and 10 adjacent the central tunnel 8 and regulated by means of suitable dampers 11. The air and/or steam admitted through tunnels 9 and 10 commingles with the fuel and air undergoing combustion from tunnel 8, assisting in controlling the combustion conditions and particularly the character of the flame in combustion zones 2 and 3 of the furnace.

The materials undergoing combustion in zones 2 and 3 of the furnace give up a major portion of their radiant energy to the fluid conduit located along the floor and roof of the combustion zones, as will be later more fully described, by means of which radiant heat is transmitted to the oil passing through the fluid conduit. The combustion gases pass from combustion zones 2 and 3 over the bridge walls 5 and 6, respectively, and pass thence downward through the so-called convection heating zone 4 of the furnace where they give up fluid heat largely by convection, although to some extent by radiation, to the fluid conduit in this portion of the furnace and to the oil passing therethrough. The spent combustion gases pass from convection zone 4 through flue 12 to a stack (not shown).

The bridge walls 5 and 6, in the particular case here illustrated, are of the suspended wall type with spaces 5' and 6', respectively, provided between their front and back walls to accommodate supporting steel structure (not shown), and, when desired, air may be circulated through the openings 5' and 6', for the purpose of cooling the steel structure and, when desired, the air thus circulated and thereby heated may be utilized as a portion or all of the air required for combustion in zones 2 and 3 of the furnace, although well known means for circulating the air through spaces 5' and 6' and for supplying to zones 2 and 3 and/or to firing tunnels 7 are not shown in the drawing.

A bank 13 of tubes 14 is located in the convection zone 4 of the furnace and consists of superimposed horizontally parallel rows of horizontal tubes. The tube bank 13 is divided into two similar sections 13' and 13'' each containing the same number of tubes and each having the same number of tubes in each horizontal row. Adjacent tubes in each row and end tubes in adjacent rows of each of the two heating coils

13' and 13'' are connected in series at their ends by means of suitable headers or return bends (not shown), and located outside of the heating zone. The single lines 15 and 16 indicate 5 the path of flow of the fluid through the heating coil, solid portions of the lines indicating the connections between the tubes on the near side of the furnace and the dotted lines indicating the connections on the far side of the furnace. The 10 arrows indicate the direction or flow of the fluid. The two streams of oil 15 and 16 of substantially equal quantities pass through the respective banks 13' and 13'' in zone 4 of the furnace where they are subjected to substantially equal 15 heating by fluid heat absorbed from the combustion gases from both of the combustion zones 2 and 3, the oil passing through this zone, in the particular case illustrated, in a general direction counter-current to the flow of combustion gases 20 therethrough.

A single row of horizontal tubes 14 comprises the floor bank 17 located adjacent the floor of combustion zone 2 and preferably, as here illustrated, depressed somewhat below the outlet from 25 firing tunnel 7 and out of the direct path of the products undergoing combustion in this zone. A roof bank 18 located adjacent the roof of combustion zone 2 comprises a single horizontal row 30 of horizontal tubes 14. Adjacent tubes in rows 17 and 18 are connected at their ends in series and the commingled streams of oil designated as 15 and 16 pass first through the floor bank 17 and then through the roof bank 18, wherein the oil is brought to the desired conversion temperature 35 derived, to some extent, by convection but primarily by radiation from the combustion gases and the heated refractory furnace walls.

Two parallel horizontal rows 19 and 20 of tubes 40 14 comprise the roof bank of the soaking section 45 of the fluid conduit located adjacent the roof of combustion zone 3. The commingled streams of oil 15 and 16 flowing through tube 14' are again split into two substantially equal streams which are designated as 15' and 16'. Stream 15' 50 enters the end tube of the exposed row 20 and stream 16' enters the adjacent tube in the same row. The respective streams then pass in parallel through adjacent tubes in shielded row 19 thence through the next two adjacent tubes in exposed row 20 and so on throughout this portion 55 of the fluid conduit.

Parallel horizontal rows 21 and 22 of tubes 14 comprise the remainder of the soaking section 55 of the fluid conduit located adjacent the floor of combustion zone 3 and, as in the case of floor bank 17, these tubes are preferably depressed somewhat below the outlet from the firing tunnel to remove them from the direct path of the materials undergoing combustion. The two 60 streams of oil 15' and 16' flow through the tubes in the shielded and exposed rows 21 and 22, respectively, of the floor bank in a manner similar to that described in connection with rows 19 and 20 of the roof bank, the two streams commingling again in the final shielded tube 14'' of the floor bank from which the heated oil is discharged to any desired further stage of the cracking process.

It will be noted that the two substantially equal streams 15' and 16' are subjected to substantially 70 equal heating conditions in the soaking section of the fluid conduit, comprising shielded rows 19 and 21 and exposed rows 20 and 22, in combustion zone 3. The two streams flow in parallel through adjacent tubes in both the shielded and exposed 75 rows, insuring that any unequal heating condi-

tions in different zones along the heating coil will not produce different heating conditions in the two streams; furthermore, the number of shielded tubes in each stream is equal to the number of shielded tubes in the other stream and the number of exposed tubes in each stream is equal to the number of exposed tubes in the other stream, insuring no inequality in the heating of the two streams, due to the different heating conditions in the shielded and exposed rows of tubes. 10

It will be understood that various modifications of the specific form of apparatus illustrated and the specific flow above described may be employed without departing from the scope of the invention. For example, the flow of oil through bank 15 13 may be concurrent instead of countercurrent to the flow of combustion gases through zone 4 of the furnace also, when desired, the direction of flow of the oil through rows 17 and 18 and/or the sequence of these two rows may be changed. 20 It is also specifically within the scope of the invention to omit the tubes in rows 18, 19 and 20 which are located above and opposed to the tubes in bank 13. When these tubes are omitted a higher proportion of radiant heat will be im- 25 parted to the tubes in the upper rows of bank 13 and consequently a somewhat higher rate of heating will occur in this portion of the fluid conduit.

I claim as my invention:

1. A furnace for heating fluid which comprises, in combination, two combustion zones, means for independently controlling the heating conditions in each combustion zone, a convection zone located between the combustion zones, means for supplying combustion gases from both of the combustion zones to the convection zone, fluid conduits comprising a plurality of elongated tubular elements located within the convection zone, means for heating said fluid conduits by fluid heat from the combustion gases, fluid conduits comprising a plurality of elongated tubular elements located in each combustion zone, means for heating the latter fluid conduits predominantly by radiant heat from the respective combustion zones, means for passing the fluid to be heated in a plurality of substantially equal streams through the fluid conduits in the convection zone in such a manner that each stream is subjected to substantially equal heating conditions therein, means for passing the fluid in a single stream through the fluid conduit in one combustion zone, and means for passing the fluid in a plurality of substantially equal streams through the fluid conduit in the other combustion zone, whereby each stream is subjected to substantially equal heating conditions in this zone. 50

2. A furnace for heating fluid which comprises, in combination, two combustion zones, means for independently controlling the heating conditions in each combustion zone, a convection zone located between the two combustion zones, means for supplying combustion gases from both of the combustion zones to the convection zone, fluid conduits comprising a plurality of elongated tubular elements located within the convection zone, means for heating said fluid conduits by fluid heat from the combustion gases, fluid conduits comprising a plurality of elongated tubular elements located in each combustion zone, means for heating the latter fluid conduits predominantly by radiant heat from the respective combustion zones, means for passing the fluid to be heated in a plurality of substantially equal streams through the fluid conduits in the con- 75

vection zone in such a manner that each stream is subjected to substantially equal heating conditions therein, means for passing the heated fluid from the convection zone in a single stream through the fluid conduit in one combustion zone, and means for finally passing the heated fluid from the latter in a plurality of substantially equal streams through the fluid conduit in the other combustion zone, whereby each stream is subjected to substantially equal heating conditions in this zone.

3. A furnace for heating fluid, which comprises, in combination, two combustion zones, means for independently controlling the heating conditions in each combustion zone, a convection zone located between the combustion zones, means for supplying combustion gases from both of the combustion zones to the convection zone, fluid conduits comprising a plurality of elongated tubular elements located within the convection zone, means for heating said fluid conduits by fluid heat from the combustion gases, a fluid conduit comprising a single row of elongated tubular elements located adjacent the floor of one combustion zone and a single row of elongated tubular elements located adjacent the roof of the same combustion zone, a fluid conduit comprising a shielded row and an exposed row of elongated tubular elements located adjacent the roof of the other combustion zone and a shielded row and exposed row of elongated tubular elements located adjacent the floor of the latter combustion zone, means for passing the fluid to be heated in a plurality of substantially equal streams through the fluid conduits in the convection zone whereby each stream is subjected to substantially equal heating conditions therein, means for passing the heated fluid from the convection zone in a single stream through the fluid conduit in the first mentioned combustion zone, and means for finally passing the heated fluid from the latter zone in two substantially equal streams through both the shielded and exposed tubes in the other combustion zone in such a manner that each stream is subjected to substantially equal heating conditions in this zone.

4. A furnace for heating fluid, which comprises, in combination, two combustion zones, means for independently controlling the heating conditions in each combustion zone, a convection zone located between the combustion zones, means for supplying combustion gases from both of the combustion zones to the convection zone, fluid conduits comprising a plurality of elongated tubular elements located within the convection zone, means for heating said fluid conduits by fluid heat from the combustion gases, a fluid conduit comprising a single row of elongated tubular elements located adjacent the floor of one combustion zone and a single row of elongated tubular elements located adjacent the roof of the same combustion zone, a fluid conduit comprising a shielded row and an exposed row of elongated tubular elements located adjacent the roof of the other combustion zone and a shielded row and exposed row of elongated tubular elements located adjacent the floor of the latter combustion zone, means for passing the fluid to be heated in a plurality of substantially equal streams through the fluid conduits in the convection zone whereby each stream is subjected to substantially equal heating conditions therein, means for passing the heated fluid from the convection zone in a single stream through the fluid conduit in the first mentioned combustion zone, and means for finally

passing the heated fluid from the latter zone in two substantially equal streams through both the shielded and exposed tubes in the other combustion zone whereby each stream passes through an equal number of exposed tubes and an equal number of shielded tubes and the two streams flow in parallel through adjacent tubes in the shielded rows and adjacent tubes in the exposed rows.

5. A process for the heating of hydrocarbon fluids which comprises heating a flowing stream of the fluid to conversion temperature in a furnace, then dividing the stream into two substantially equal streams, passing the latter streams simultaneously through a fluid conduit located within the furnace, said fluid conduit comprising a shielded row and an exposed row of parallel elongated tubular elements subjected to heating primarily by radiation, passing each stream through diagonally adjacent tubes in the two rows and through alternate tubes in each row, the two streams passing in parallel through adjacent tubes in the same row in such a manner that each stream flows through the same number of exposed tubes and through the same number of shielded tubes, whereby a substantially equal quantity of fluid passes through each stream and each stream is subjected to substantially equal heating conditions.

6. In the heating of hydrocarbon fluid in furnaces of the type having a pair of independently fired combustion zones and a convection zone receiving combustion gases from both the combustion zones; the method which comprises first passing the hydrocarbon fluid through the convection zone and subjecting the same therein to convection heating from said gases, then passing the fluid in a stream through one of said combustion zones and further heating the same therein predominantly by radiant heat, raising the fluid to conversion temperature during its flow through the convection zone and the last named combustion zone, dividing said stream, after elevation of the fluid to conversion temperature, into a plurality of substantially equal streams and passing the latter through the other of said combustion zones wherein the fluid is maintained at conversion temperature predominantly by radiant heat, and subjecting the equal streams to substantially uniform heating conditions during their passage through the last named combustion zone.

7. In the heating of hydrocarbon fluid in furnaces of the type having a pair of independently fired combustion zones and a convection zone receiving combustion gases from both the combustion zones; the method which comprises first passing the hydrocarbon fluid through the convection zone in a plurality of streams and subjecting the same therein to convection heating from said gases, then uniting said streams and passing the resultant composite stream through one of said combustion zones, heating the composite stream in the last named combustion zone to conversion temperature predominantly by radiant heat, then dividing the composite stream into a plurality of substantially equal streams and passing the latter through the other of said combustion zones wherein the fluid is maintained at conversion temperature predominantly by radiant heat, and subjecting the equal streams to substantially uniform heating conditions during their passage through the last named combustion zone.

8. In the heating and subjecting of hydrocar-

bon fluids to conversion temperatures in furnaces of the type having a pair of independently fired radiant heat zones and a convection heating zone receiving combustion gases from both the radiant heat zones, the method which comprises first passing the hydrocarbon fluid through said convection zone, then passing the fluid in a single stream through one tube bank adjacent the floor and through another adjacent the roof of one of said radiant heat zones and heating the same in this zone predominantly by radiation, then dividing said single stream into a plurality of substantially equal streams and passing the latter through one tube bank adjacent the roof and through another adjacent the floor of the other of said radiant heat zones, and subjecting the equal streams to substantially uniform radiant heating conditions during their flow through said other radiant heat zone.

20 9. In the heating and subjection of hydrocarbon fluids to conversion temperatures in furnaces of the type having a pair of independently fired radiant heat zones and a convection heating zone receiving combustion gases from both the radiant heat zones, the method which comprises first passing the hydrocarbon fluid through said convection zone in a plurality of streams, then combining said streams and passing the resultant single stream through one tube bank adjacent the floor and through another adjacent the roof of one of said radiant heat zones and heating the same in this zone predominantly by radiation, then dividing said single stream into a plurality of substantially equal streams and passing

the latter through one tube bank adjacent the roof and through another adjacent the floor of the other of said radiant heat zones, and subjecting the equal streams to substantially uniform radiant heating conditions during their flow 5 through said other radiant heat zone.

10. In the heating of hydrocarbon fluid in furnaces of the type having a pair of independently fired combustion zones and a convection zone receiving combustion gases from both the combustion zones; the method which comprises heating the hydrocarbon fluid to conversion temperature by passage through the convection zone and one of said combustion zones, the fluid being heated predominantly by convection from said gases in 15 the convection zone and predominantly by radiant heat in the combustion zone and the fluid being passed through the latter zone in a single stream, dividing said single stream, after elevation thereof to conversion temperature, into a 20 plurality of substantially equal streams and passing the latter through the other of said combustion zones wherein the fluid is maintained at conversion temperature predominantly by radiant heat, and subjecting the equal streams to 25 substantially uniform heating conditions during their passage through the last named combustion zone.

11. The method as defined in claim 10 further characterized in that the hydrocarbon fluid undergoing heating is passed through the convection zone in a plurality of streams.

MARION W. BARNES.
